Primary Examiner — Sheryl Lane*Assistant Examiner* — Samantha N Wood(74) *Attorney, Agent, or Firm* — Quickpatents, LLC;
Kevin Prince(57) **CLAIM**

I claim the ornamental design for a figurine leg and foot, as shown and described.

DESCRIPTION

FIG. 1 is a top perspective view of a figurine leg and foot, showing my new design;

FIG. 2 is a bottom perspective view thereof;

FIG. 3 is a left-side elevational view thereof;

FIG. 4 is a right-side elevational view thereof;

FIG. 5 is a front elevational view thereof;

FIG. 6 is a rear elevational view thereof;

FIG. 7 is a top plan view thereof; and,

FIG. 8 is a bottom plan view thereof.

The broken lines in the drawings illustrate portions of the figurine leg and foot that form no part of the claimed design.
